UNITED STATES PATENT OFFICE.

JOHN MACKEY, OF CAPE HORN, WASHINGTON.

INVALID-BED.

No. 924,083.

Specification of Letters Patent.

Patented June 8, 1909.

Application filed August 24, 1908. Serial No. 449,961.

To all whom it may concern:

Be it known that I, JOHN MACKEY, a citizen of the United States, residing at Cape Horn, in the county of Skamania and State 5 of Washington, have invented certain new and useful Improvements in Invalid-Beds, of which the following is a specification.

This invention relates to beds and has special reference to a device of this character 10 which is peculiarly adapted for the comfort of invalids.

An object of this invention is to provide a bed of this character with a swinging head section by means of which the patient may 15 be raised conveniently to a sitting posture at various angles.

The invention has for a further object the provision of a table attached to the bed which may be adjusted to different angles 20 and positions according to the requirements.

The invention has for a still further object a pivoted head section of peculiar construction which renders it strong and durable and more adaptable to practical use 25 than constructions heretofore employed.

Other objects and advantages will be apparent from the following description and it will be understood that changes in the specific structure shown and described may 30 be made within the scope of the claim without departing from the spirit of the invention.

In the drawings forming a portion of this specification, and in which like numerals of 35 reference indicate similar parts in the several views, Figure 1 is a side elevation of the complete bed, Fig. 2 is a top plan view of the same, Fig. 3 is a detailed and enlarged view of the table and its supporting means, 40 Fig. 4 is a longitudinal vertical section of the bed with the head section slightly raised.

Referring to the drawings, 10 and 11 designate the foot-board and head-board of the bed respectively which support the sides 12 45 and 13 between their opposite intermediate edges. The sides 12 and 13 are each recessed transversely at their inner edges as at 14 and are provided with undercut recesses 15 formed adjacent and connected to the recesses 14 at the lower edges of the sides 12 and 13. The sides 12 and 13 carry the opposite extremities of a transverse shaft 16 which is engaged in apertures formed at the lower edges of the sides 12 and 13 and is 50 further secured in position by plates 17 disposed across the under sides of the shaft 16

upon the lower edges of the sides 12 and 13. The shaft 16 is provided with pinions 18 which are rigidly mounted upon the shaft and which extend partially into the recesses 15 formed in the inner faces of the sides 12 and 13. The shaft 16 extends beyond the side 13 and rigidly carries a ratchet 19 which meshes with a pawl 20 pivotally disposed upon the outer face of the side 13 for the purpose of preventing the opposite or backward rotation of the shaft 16. The outer extremity of the shaft 16 is rectangularly formed for the reception of a crank arm 21 which is used for the purpose of rotating the shaft 16. Upon the inner faces of the sides 12 and 13 centrally of the shaft 16 are pivotally mounted two beams 22 and 23 which extend to the head 11 when dropped in parallel with the sides and which are provided with extensions 24 to engage upon a cross brace 25 positioned transversely of the head 11. The beams 22 and 23 are strengthened by a cross beam 26 which is secured between the free extremities of the beams 22 and 23. The beams 22 and 23 are raised 70 into various angles by means of the segmental racks 27 and 28 which are secured upon the outer faces of the beams 22 and 23 and extend downwardly into the recesses 14 formed in the inner faces of the sides 12 and 13. When the segmental racks 27 and 28 are in this position the teeth, which are 75 formed upon the inner edge of the racks engage against the pinions 18 and are actuated thereby. The segmental racks 27 and 28 are held in position in the recesses 14 by the plates 28' which are secured upon the inner faces of the sides 12 and 13 and extend over the slots 14 to engage the inner faces of the 80 racks 27 and 28.

The table which is employed in connection with this bed is constructed as follows. A U shaped clamp 30 is secured to the outer face of the side 13 which is provided with a vertical aperture extending through the same into which is positioned a rod 31 and held in such position by a pin 32 of wedge shape which is adapted to extend laterally into the clamp 30 and impinge the rod 31 against the clamp 30. At the upper extremity of the rod 31 there is positioned a horizontally disposed table 33 which is provided upon its under face with a sleeve 34 into which the upper curved extremity of the rod 31 is inserted and adjustably secured in such sleeve by a set screw 35. When it is desired 90

to raise the rod 31 to obtain a greater height of the table 33 the pin 32 is removed and the rod 31 is raised through the U shaped clamp 30 when the pin 32 is reset 5 and driven into the clamp 30 to secure a wedging of the rod 31 within the clamp. When it is desired to position the table at the extremity of the arm 31 the set screw 35 is loosened and the sleeve 34 together with 10 the table 33 is allowed free movement over the upper extremity of the same. It is thus seen that the table 33 may be readily adjusted as to its height and horizontal position. When it is desired to raise the head section 15 the crank arm 21 is positioned upon the shaft 16 and rotated. This rotation causes the upwardly feeding of the segmental racks 27 and 28 to raise the beams 22 and 23 and to thus raise the patient to a sitting posture 20 at practically the desired angle. The pawl 20 engaging the ratchet 19 holds the frame at the angle through which it is raised and prevents it from dropping backwardly.

What is claimed is:—

25 As an article of manufacture, an invalid bed comprising a head board, a foot board, sides disposed between said head board and said foot board, said sides having transverse arcuate recesses and undercut recesses formed

in the inner faces thereof, the recesses being 30 in communication with each other, a shaft disposed transversely from the undercut recesses between said sides, pinions mounted on the extremities of said shaft, a ratchet carried on one end of said shaft outwardly 35 of one of said pinions against the outer face of one of said sides, a pawl carried by said side for engagement with said ratchet, a crank arm detachably disposed on said shaft for rotating the same, beams pivotally 40 disposed in parallel upon the inner opposite faces of said sides, a cross brace carried by said head board, extensions formed on the ends of said beams for engagement with said brace, a cross beam carried by said 45 beams, segmental racks depended from the outer ends of said beams and engaged in the arcuate recesses in said sides and with said pinions, and plates positioned on said sides extended over said recesses in engagement 50 with said rack to hold the same in position.

In testimony whereof I affix my signature, in presence of two witnesses.

JOHN MACKAY.
